UNITED STATES PATENT OFFICE.

JOHN R. DEAN, OF WESLEYVILLE, PENNSYLVANIA.

CORSET-STAY.

No. 868,763.

Specification of Letters Patent.

Patented Oct. 22, 1907.

Application filed July 8, 1907. Serial No. 382,622.

To all whom it may concern:

Be it known that I, JOHN R. DEAN, a citizen of the United States, residing at Wesleyville, in the county of Erie and State of Pennsylvania, have invented new and useful Improvements in Corset-Stays, of which the following is a specification.

This invention relates to improvements in the construction of stays or stiffeners for corsets and other similar wearing apparel.

10 The invention is illustrated in the accompanying drawing.

Figure 1 shows a plan view of a stay formed of two wires. Fig. 2 a section on the line 2—2 in Fig. 1. Fig. 3 a plan view formed of one wire. Fig. 4 a section on the line of 4—4 in Fig. 3.

In the preferred construction having a plurality of wires 1—1 marks the wires. These may be of any preferred cross section. The loops 2 are preferably pear shaped as shown, and are oppositely disposed so

20 as to form a comparatively even edge.

An important feature of the invention consists in the manner of arranging the loops with relation to each other.

It will be noted that all the loops over-lap at 4 along 25 the top and that all the loops cross or are inter-woven or inter-locked along the bottom at 3. By inter-weaving one edge the position of the loops with relation to each other is fixed so that the general shape of the stay is maintained, even with fragile wire, and by 30 loosely disposing the loops along the opposite edge the stay is given flexibility; and where they are over-lapped the stay still has this flexibility but the loops are better secured.

The strength of the stay may be increased or diminished by forming the loops more closely together or

farther apart. This varies the amount of wire in a given distance and, of course, varies the strength accordingly.

In the one wire construction shown in Figs. 3 and 4, 1^a marks the wire; 2^a, the loops; 3^a, the inter-woven or 40 inter-locked portion, and 4^a, the over-lapped portion. It has the main characteristics of the construction, formed by the plurality of wires, shown in Fig. 1.

Instead of the usual metal cap with which the ends of the wires are secured, I prefer to secure them by 45 soldering the ends to a preceding loop and use sufficient solder to fill the space between the wires. This gives a light, yet secure means of fastening the wires.

The number of strands may be varied. I prefer, however the two strand structure shown in Figs. 1 and 2. 50

What I claim as new is:

1. A stay for corsets and similar articles comprising a flat wire spring formed of oppositely disposed loops, the loops being inter-woven along one edge and loosely disposed along the opposite edge. 55

2. A stay for corsets and similar articles comprising a flat wire spring formed of oppositely disposed loops, the loops being inter-woven along one edge and over-lapped along the opposite edge.

3. A stay for corsets and similar articles comprising a flat wire spring formed of oppositely disposed loops with a plurality of wires, the loops being inter-woven along one edge and loosely disposed along the opposite edge. 60

4. A stay for corsets and similar articles comprising a flat wire spring formed of oppositely disposed pear shaped loops with a plurality of wires, the loops being inter-woven along one edge and over-lapped along the opposite edge. 65

In testimony whereof I have hereunto set my hand in the presence of two subscribing witnesses.

JOHN R. DEAN.
